DESIGN FOR A FRUIT JUICE EXTRACTOR

Lewis H. Scurlock, Chicago, Ill.

Application March 23, 1938, Serial No. 76,035

Term of patent 3½ years

To all whom it may concern:

Be it known that I, Lewis H. Scurlock, a citizen of the United States and resident of Chicago, in the county of Cook and State of Illinois, have invented a new, original, and ornamental Design for a Fruit Juice Extractor, of which the following is a specification, reference being had to the accompanying drawing, forming a part thereof.

Fig. 1 is a front elevation of a fruit juice extractor, showing my new design.

Fig. 2 is a side elevation of said fruit juice extractor.

Fig. 3 is a horizontal section on line 3—3 in Fig. 2 of the drawing.

I claim:

The ornamental design for a fruit juice extractor, as shown.

LEWIS H. SCURLOCK.
